Attorney.

UNITED STATES PATENT OFFICE.

JOHN H. CARSON, OF LOS ANGELES, CALIFORNIA.

PUMPING JACK.

Application filed November 18, 1922. Serial No. 601,834.

To all whom it may concern:

Be it known that I, JOHN H. CARSON, a citizen of the United States, residing at Los Angeles, in the county of Los Angeles and State of California, have invented a new and useful Pumping Jack, of which the following is a specification.

My invention relates to pumping jacks for deep wells; and has for its salient objects, first, to provide a simple rig adapted for cable operation and readily attachable to a well casing in situ; second, to afford facilities for engaging the polish rod for operation at any desired position of the latter; and, third, to furnish means for varying the throw or travel of the pump rod.

Other objects and advantages will appear hereinafter, and while I show herewith and will describe a preferred form of construction, I desire to be understood that I do not limit myself to such form, since various changes and adaptations may be made therein without departing from the spirit of my invention as hereinafter claimed.

My objects are attained by means of the mechanism illustrated in the accompanying drawing, in which—

Figure 1 is a side elevation, and Figure 2 is an end elevation, of my improved jack in place on a well casing. Figure 3 is a plan view of the same. Similar numerals refer to similar parts throughout the several views.

The form of my invention selected for illustrative purposes comprises a pair of base timbers 1 having centrally positioned saddle blocks 2, held together by bolts 3. By means of the latter the base may be tightly clamped upon a well casing 4 at any desired position below the casing head 5.

On the base timbers are mounted four pillow blocks 6 and each pair of these carries a transverse rocker shaft 7. Each of these shafts has an overhung bifurcated crank 8 keyed thereto, and these are linked together by connecting rod 9 in such manner that they are constrained to rotate in opposite directions through their operating angles.

Shafts 7 carry rocker arms 10 centrally affixed thereto, and these in turn are connected by links 11 to toggle arms 12. The latter are connected together by a pair of central links 13, and are provided with con-

cave gripping jaws 14 at their inner ends. Jaws 14 are eccentric with respect to pins 15, about which they are adapted to swing, and in this way they are enabled to exert a very powerful toggle grip upon polish rod 16 which operates the pump plunger in the well casing.

An actuating crank 17 is affixed to either of the rocker shafts, and cable 18 is attached thereto in such a manner that a sufficient pull exerted by the cable will cause the mechanism to lift the polish rod. The weight of the latter, together with that of the pump plunger and parts depending therefrom, will serve to restore the mechanism to the position it assumes at the bottom of its stroke as soon as the pull on the cable is released. Obviously therefore a reciprocating up and down motion will be imparted to the polish rod by alternately pulling on and slackening off the cable in the manner commonly employed for pumping in oil districts and similar situations.

The pumping mechanism proper forms no part of the present invention and therefore is not shown. It may consist of any suitable plunger and working barrel at any depth within casing 4, or the latter may be used as the working barrel. As depicted I have shown the casing head provided with an outlet orifice 19, and a gland 20 surrounding the polish rod.

It will be noted that the weight of the depending parts will not only serve to restore the mechanism to its low position as explained, but will also continuously maintain the toggle grip on the polish rod unless it is intentionally released. Furthermore it will be seen that this grip may be applied at any point on the rod, permitting of lengthening the latter and pumping at any desired depth.

For securing a variable stroke of the polish rod, I provide rocker arms 10, and toggle arms 12, with a series of holes as 21 and 22 respectively. By changing the connecting pins of links 11 to these other respective holes, a variation in the throw of the mechanism is effected.

The alignment of the polish rod is maintained by gland 20, and this in turn maintains the alignment of the rest of the mechanism.

The concave surfaces of the toggle grips are preferably knurled or otherwise mutilated.

I claim as my invention;

5 A pump jack comprising a frame adapted for clamping on a well casing; horizontal rocker shafts rotatably mounted on said

frame and having arms affixed thereto; a toggle grip supported by said arms and therebetween; and means for oppositely oscillating said shafts to vertically reciprocate said grip.

10

JOHN H. CARSON.
